UNITED STATES PATENT OFFICE.

SAMUEL MARTIN, OF MILL ROCK, OHIO.

VELOCIPED.

SPECIFICATION forming part of Letters Patent No. 340,340, dated April 20, 1886.

Application filed October 31, 1885. Serial No. 181,472. (No model.)

To all whom it may concern:

Be it known that I, SAMUEL MARTIN, of Mill Rock, in the county of Columbiana and State of Ohio, have invented certain new and 5 useful Improvements in Tricycles, of which the following is a full, clear, and exact description.

The object of my invention is to provide a new and improved tricycle, which can be propelled by one, two, or more persons, and is especially adapted to attain a great rate of speed and to carry passengers or freight.

The invention consists of two driving-wheels actuated by hand and foot levers and 15 suitable ratchet-wheel connections, of a shaft on which is mounted the driving-gear, a swinging frame and seat, of a guide-wheel mounted in turning bearings held in place by suitable connections from the main axle, of a 20 device for operating the guide-wheel, and of a brake of special construction.

The invention also consists of various parts and details, hereinafter more fully set forth and claimed.

Reference is to be had to the accompanying drawings, forming part of this specification, in which similar letters of reference indicate corresponding parts in all the figures.

Figure 1 is a plan view, partly in section, of 30 my improvement. Fig. 2 is a longitudinal vertical section on the lines *x x* of Fig. 1. Fig. 3 is a vertical cross-section on the lines *y y* of Fig. 1. Figs. 4 and 5 are detail views of the driving-wheel hub and ratchet-block. 35 Figs. 6 and 7 are detail views of the ratchet-wheel. Figs. 8, 9, and 10 are detail views of the lever and wheel carrying the sliding ratchet-wheel pawls. Fig. 11 is a sectional plan view of the guide-wheel fastening. Fig. 40 12 is a longitudinal vertical section of the machine, the guiding-wheel and connections being detached and parts broken away. Fig. 13 is a front elevation showing the frame and brake system.

The main shaft *A* is provided near each end 45 with the hubs *B B*, turning loosely on the shaft *A*, and on which hubs *B B* are mounted the driving-wheels *C C*. The hubs *B B* are provided with recesses *B'* on their outer faces, 50 in which recesses *B'* are formed the ratchet-teeth *B''*. The shaft *A* projects into each re-

cess *B'* with its square ends *A' A'*, on which are secured the ratchet-blocks *D*, having each a recess, *D'*, in which slide the pawls *D''*, and held in contact with the ratchet-teeth *B''* by 55 the force of the coiled springs *D''*, placed in the recess *D'* between the axle end *A'* and the pawls *D''*. A cover, *D'*, is placed over the outer open face of the hub *B*, and secured by the nut *D''* screwing on a bolt formed on the 60 extreme end of the shaft *A*. This cover *D'* protects the ratchet-block *D* from dust and mud. Next to the inner edge of the hub *B* is placed on the shaft *A* the sleeve *E*, provided on its rim with a screw-thread, on which is 65 screwed the frame-block *E'*, to which is attached the main frame *F*. The frame *F* consists, principally, of the horizontal arms *F'*, attached to the frame-blocks *E'* of the horizontal connecting-rod *F''*, from which project downwardly the stays *F''*, on the lower end of which is hung the front end of the swinging platform *G*. 70

To the rear end of the frame-block *E'* are secured the forked stays *F''*, to which are attached the upright rods *F''*, to the lower end of which is hung the rear end of the swinging platform *G*, and which rods *F''* are connected by the horizontal connecting-rod *F''*. 75

To each of the arms *F'* is attached an upright 80 rod, *F''*, which is on its lower end connected by the rod *F''* with the arm *F''*, and on its upper end by the stay *F''* to the upright *F''*, and by the inclined stay *F''* to the connecting-rod *F''*. The lower ends of the upright rods *F'' F''* 85 are connected to each other by the horizontal rod *F''*, and the lower ends of the vertical rods *F'' F''* are connected to each other by the horizontal rod *F''*.

To the cross-rods *F'' F''*, and *F'' F''* are pivoted 90 the bent rods *G'*, to which are pivotally connected the arms *G''*, attached to the under side of the swinging platform *G*.

Next to the sleeve *E* on the shaft *A* is placed the wheel *H*, carrying the four or more 95 pawls, *H'*, sliding in sleeves *H''*, formed on the wheel *H*, and held in contact with the ratchet-teeth *I*, formed on the outer face of the ratchet-wheel *I*, by the force of the coiled springs *H''*. The wheel *H* is provided with a 100 hub, *H''*, in contact with the inner edge of the sleeve *E*, and around which hub *H''* is placed

a coiled spring, H^3 , fastened to the wheel H at one end, the other end being secured to the sleeve E . The wheel H is also provided with the offsets H^6 , on which is pivoted the forked

5 lever H^7 , by which the wheel H can be turned on the shaft A . The lever H^7 rests in its normal position on the rod F^2 , as shown in Fig. 12.

The ratchet-wheel I is secured to the shaft A in any suitable manner, and is provided on 10 each face with the ratchet-teeth I' .

On the hub I^2 of the ratchet-wheel I is placed the belt-pulley J , which turns on the same, and is prevented from slipping off the said hub I^2 by the nut I^3 , screwed on the inner 15 end of the hub I^2 . The belt-pulley J is provided with sleeves J' , in which slide the pawls J^2 , held against the ratchet-teeth I' formed on the inner side of the ratchet-wheel I , by the force of the coiled spring J^3 . It will be seen 20 that the ratchet-teeth I' , formed on each face of the ratchet-wheel I , are engaged on the outer edge by the sliding pawls H' of the wheel H , and on the inner edge by the sliding pawls J^2 of the belt-pulley J .

25 To the connecting-rod F^6 are pivoted the lower ends of the levers K , which extend in an inclined position upward, and are provided with the handles K' . To each of these levers K is attached the end of a belt, K^2 , which 30 passes downward and over a pulley, K^3 , placed on the cross-rod F^{12} , and upward over the belt-pulley J , to the rim of which the other end of the belt K^2 is attached.

To the belt K^2 is buckled a short strip, K^4 , 35 of leather or other material, to which strip K^4 is attached the stirrup K^5 , having a foot-piece, K^6 , and sliding on the inclined rods G^3 , attached to the platform G . It will be understood that by raising the levers K , in the direction of the arrow a' , and at the same time pressing the stirrups K^5 , which slide on the rods G^3 downward, it will cause the pulley J to turn on the hub I^2 of the ratchet-wheel I by 40 means of the belt K^2 . The coiled spring K^7 , attached to the rod F^3 , will assist the lever K to resume its former position on the return-stroke of the same in the direction of the arrow a' .

To the belt-pulley J is attached one end of 50 a coiled spring, J^4 , the other end of the same being secured to a forked brace, J^5 , which has its lower bearing on the cross-rod F^{12} , and its upper forked end being placed over the shaft A . This coiled spring J^4 assists the lever K to assume its former position on the return-stroke in the direction of the arrow a' . Rods G^4 , similar to rods G^3 , extend from the rear of the platform G upward, and they and the rods G^3 carry the seat G^5 , which is thus suspended 55 centrally in the middle above the axle A , and conveniently large to admit two or more persons. The guide-wheel L is mounted in segmental pieces L' , which are provided on their outer rims with grooves L^2 , in which fit the blocks M , bolted to the castings M' , which are held in position by the inclined stay-rods M^2 , secured to the main frame F at the horizontal

cross-rod F^2 , and additionally braced by the rods M^3 , extending from the forked rods F^4 to the cross-rod F^{11} , and from thence to the castings M' .

To the shaft L^3 of the guide-wheel L are attached the outer ends of the forks N' of the lever N , which imparts a turning motion to the guide-wheel L by the device now to be described.

To the horizontal cross-rod F^2 is secured the curved rack O , provided with the teeth O' , in which engages the pointed pawl O^2 , placed on the lever-frame P , and held in contact with the teeth O' by the force of the spring O^3 . The lever-frame P is provided with the handle P' and the two small rollers $P^2 P^2$, pivoted to the frame P , one at each side of the pawl O^2 , and resting against the edge of the rack O , so that when the handle P' is moved to either side it will cause the pawl O^2 to disengage the rack O , and at the same time will swing the lever N sidewise, and consequently turn the guide-wheel L . The lever N may be 90 locked in such side position by allowing the pawl O^2 to again engage the respective teeth O' on the rack O , the handle P' and the frame P projecting radially from the guide-wheel L .

To the outer ends of the horizontal rods F^2 95 are attached the brakes $Q Q'$, one for each driving-wheel C . Each of the brakes Q consists, principally, of the brake-frame Q' , to the upper end of which is attached the forked brake-shoe Q^2 . The brake frame Q' is provided with a slot, Q^3 , through which passes the cross-rod F^2 , so that when the brake-frame Q' is pressed downward the brake-shoe Q^2 is forced against the rim of the driving-wheel C . The lower end of the brake-frame Q' is secured 105 to a lever, U , pivotally attached to the lower cross-rod, F^{11} . This lever U is also provided with brake-shoes U' , and is held in its normal position, as shown in Figs. 12 and 13, by a spring, U^2 , attached to the lever U and the cross-rod F^{11} . The levers U are connected with each other by the arms U^3 and the cross-rod U^4 . It will be seen that by pressing the cross-rod U^4 downward with the feet it causes the brake-shoes Q^2 and U' to engage the rims 110 of the wheels C , and when the downward pressure on the cross-rod U^4 ceases then the springs U^2 will force the levers U to their former position, thereby releasing the brake-shoes Q^2 and U' from the rims of the wheels C .

115 The operation is as follows: The levers H^7 are raised from their normal position (shown in Fig. 12) and are moved upward by the operator in the direction of the arrow b^2 until they assume the position shown in Fig. 2. 120 The levers H^7 are then moved downward by the operator in the direction of the arrow b^2 , which causes the ratchet-wheel I , and consequently the shaft A , to rotate. The shaft A receives a similar motion by means of the lever K , the belt K^2 , and the stirrup K^3 by raising the lever K in the inverse direction of the arrow a' , causing the belt-pulley J to rotate, which transmits its rotation by means of the pawls

J' to the ratchet-wheel I, and the latter, being secured to the shaft A, causes the shaft A to revolve, and consequently the driving-wheel C by the arrangement in the hub B, as before described. The levers H' are operated by one person standing on the swinging platform G, and the levers K are simultaneously raised with the hands of another person seated in the seat G⁵ at the same time that the feet of this operator, placed in the stirrups K⁵, press the latter downward, thus transmitting double power to the belt-pulley J. The action of both operators on the levers H' and K and the stirrups K⁵ causes the shaft A to revolve in the same direction, and thus propel the machine forward by the united power of the two operators.

The swinging platform G affords easy riding on driving the tricycle over uneven or rough ground.

Having thus fully described my invention, I claim as new and desire to secure by Letters Patent—

1. In a tricycle, the shaft A, the ratchet-block D, provided with the slot D', the sliding pawls D², the springs D³, the hubs B, and the driving-wheels C, all arranged as shown and described.

2. In a tricycle, the shaft A, the wheel I, and the ratchet-teeth I', in combination with the wheel H, the sliding pawls H', the springs H³, and the lever H', substantially as shown and described.

3. In a tricycle, the shaft A, the wheel I, and the ratchet-teeth I', in combination with the belt-pulley J, the sliding spring-pawls J², the belt K², and the lever K, substantially as shown and described.

4. In a tricycle, the shaft A, the wheel I, the ratchet-teeth I', the ratchet-block D, the sliding pawls D², the springs D³, the hubs B, and the driving-wheels C, in combination with the wheel H, the sliding pawls H', the lever H', the belt-pulley J, the sliding pawls J², the lever K, and the belt K², substantially as shown and described.

5. In a tricycle, the combination of the shaft A, the hub B, the driving-wheels C, the frame F, the swinging platform G, and the seat G⁵, substantially as shown and described.

6. In a tricycle, the combination of the shaft A, the hub B, the driving-wheels C, the frame F, the supports M² and M³, the block M, the segments L, having recesses L², and the guiding-wheel L, substantially as shown and described.

7. In a tricycle, the guiding-wheel L, the segments L', having the recesses L² and the supporting-blocks M, in combination with the forked lever N, the rack O, the teeth O', the pawl O², and the lever-frame P, provided with the handle P' and the rollers P², substantially as shown and described.

8. In a tricycle, the forked lever N, the lever-frame P, the handle P', the rollers P², the pawl O², and the spring O³, in combination

with the rack O, the teeth O', and the guide-wheel L, substantially as shown and described.

9. In a tricycle, the combination of the guide-wheel L, the segments L', the recesses L², the blocks M, and the castings M', supported from the main frame F by the rods M² and M³, substantially as shown and described.

10. In a tricycle, the combination, with the shaft A, the sleeve E, the frame-block E', the frame F, the swinging platform G, and the seat G⁵, substantially as shown and described.

11. In a tricycle, the combination, with the shaft A, the sleeve E, the frame-block E', the frame F, the swinging platform G, the seat G⁵, the supports M² and M³, the driving-wheels C, and the guide-wheel L, all arranged substantially as shown and described.

12. In a tricycle, the shaft A, the ratchet-blocks D, the pawls D², the hubs B, the driving-wheels C, and the wheels I, provided with teeth I' on each side, in combination with the wheels H, the spring-pawls H', the springs H³, the levers H', the belt-pulleys J, the pawls J², the levers K, the belts K², the straps K⁴, and the stirrups K⁵, substantially as shown and described.

13. In a tricycle, the shaft A, the wheel I, the ratchet-teeth I', the hub I², and the nut I³, in combination with the belt-pulley J, the pawls J², the springs J³ and J⁴, the forked arm J⁵, the lever K, the spring K⁷, the belt K², the strap K⁴, and the stirrup K⁵, sliding on the rod G³, all arranged substantially as shown and described.

14. In a tricycle, the combination of the shaft A, the hubs B, the driving-wheels C, the pawl-block D, the sleeve E, the frame-block E', the frame F, the swinging platform G, the seat G⁵, the wheel H, the spring-pawls H', the wheel I, the ratchet-teeth I', the belt-pulley J, the spring-pawls J², the spring J⁴, the forked arm J⁵, the lever K, the spring K⁷, the belt K², the pulleys K⁸, the adjustable straps K⁴, the stirrup K⁵, the guiding-wheel L, the segment L', the block M, the casting M', supported by the rods M² and M³, the forked lever N, the toothed rack O, the lever-frame P, the handle P', the rollers P², and the pawl O², all arranged substantially as shown and described.

15. In a tricycle, the brake-frame Q', having a slot, Q³, and the brake-shoe Q², in combination with the lever U, the brake-shoe U', the spring U², the arm U³, and the cross-rod U⁴, substantially as shown and described.

16. In a tricycle, the brake-frame Q', having a slot, Q³, the brake-shoes Q² and U', the lever U, the spring U², the arm U³, and the cross-rod U⁴, in combination with the cross-rod F² and F³, of the main frame F, and the driving-wheels C, substantially as shown and described.
